UNITED STATES PATENT OFFICE.

OTTO J. DOERRE, OF CHICAGO, ILLINOIS, ASSIGNOR TO CHICAGO PAPIER-MACHE CO.,
OF CHICAGO, ILLINOIS, A CORPORATION OF ILLINOIS.

DESIGN FOR A LAMP-BASE.

59,581.

Specification for Design.

Patented Nov. 8, 1921.

Application filed January 17, 1921. Serial No. 438,018. Term of patent 3½ years.

To all whom it may concern:

Be it known that I, OTTO J. DOERRE, a citizen of the United States, residing in the city of Chicago, county of Cook, and State of Illinois, have invented a new, original, and ornamental Design for a Lamp-Base, of which the following is a specification, reference being had to the accompanying drawings, forming part thereof.

I claim:

The ornamental design for a lamp base, substantially as shown.

OTTO J. DOERRE.
